UNITED STATES PATENT OFFICE.

JULIAN H. RIVERS, OF ST. LOUIS, MISSOURI, ASSIGNOR TO UNITED STATES FIBER STOPPER COMPANY, OF ST. LOUIS, MISSOURI, A CORPORATION OF SOUTH DAKOTA.

APPARATUS FOR TREATING PULP-STOCK.

SPECIFICATION forming part of Letters Patent No. 768,305, dated August 23, 1904.

Application filed March 13, 1903. Serial No. 147,635. (No model.)

To all whom it may concern:

Be it known that I, JULIAN H. RIVERS, a citizen of the United States, residing at St. Louis, Missouri, have invented a certain new and useful Improvement in Apparatus for Treating Pulp-Stock, of which the following is a full, clear, and exact description, such as will enable others skilled in the art to which it app pertains to make and use the same, reference being had to the accompanying drawings, forming part of this specification, in which—

Figure 1 is a side elevation of the entire apparatus. Fig. 2 is an end view looking from the left of Fig. 1, the forming-machine being removed and the exhaust-pipe being broken. Fig. 3 is a top plan view of the condensing mechanism. Fig. 4 is a central longitudinal sectional elevation of the same. Fig. 5 is a transverse sectional elevation on the line 5 5 of Fig. 4. Fig. 6 is a side elevation of the drying or bat-forming device. Fig. 7 is a transverse sectional elevation of the same. Fig. 8 is a detail view of the hopper and the governor, said hopper being shown in sectional elevation. Fig. 9 is a top plan view of the hopper and its valve mechanism, and Fig. 10 is a detail view.

My invention relates to apparatus for treating pulp-stock.

Among my objects are to provide an apparatus by means of which the pulp in a relatively fluid condition will be so treated that it can be fed from the apparatus in such condition that it can be readily acted upon by a forming-machine or the like, to provide means whereby the supply of pulp to the apparatus is automatically maintained properly proportioned with relation to the output of the apparatus to provide means whereby the pulp can be efficiently preliminarily dried and formed into a thin bat, to provide means whereby without interfering with the proper preliminary drying a relatively large amount of pulp in its preliminarily-dried condition can be fed to the condensing mechanism, to provide means for gradually condensing the pulp, and to provide means for extracting moisture from the pulp while such pulp is being fed to the

condensing devices and at the same time assisting in such feeding of the pulp.

To these ends and also to improve generally upon apparatus of the character indicated my invention consists in the various matters hereinafter described and claimed.

Generally considered the present apparatus 55 comprises a hopper or reservoir A, a drying or bat-forming device B, and a condensing mechanism C, the drawings illustrating the present embodiment of my invention showing the condensing mechanism delivering to a 60 suitable forming-machine D and showing the various parts and mechanisms supported upon a suitable frame E. The governor for controlling the valve for the discharge-opening in the hopper or reservoir is marked F.

The pulp in a highly-fluid condition is delivered to the hopper or reservoir A in any suitable manner and is fed from the same to the drying or bat-forming device B, from which it is delivered in a thin bat to a traveling screen, which may be termed a portion of the condensing mechanism. This screen carries the pulp beneath certain condensing-rollers and then delivers the condensed pulp mass or web to the forming-machine D. During the time that the pulp is spread upon the before-mentioned screen of the condensing mechanism it is subjected to the influence of suction, by means of which the pulp is held upon the said screen and moisture is extracted 75 from said pulp.

The frame.—The frame can be of any suitable construction, and I have here shown the same as made of lengths of gas-pipe suitably connected. In the frame illustrated I have 85 provided what may be termed "intermediate uprights" 1, which are connected at their upper portions by cross-bars 2 and 3, arranged one below the other, a third cross-bar 4 being arranged slightly below the before-mentioned 90 lower cross-bar 3. Extending laterally upon one side of each of the said intermediate supports 1 are horizontal upper and lower bars 5 and 6, which are connected at their outer ends by a vertical bar 7, whereby substantially rectangular frames are produced, suit-

able inclined braces 8 extending between the outer ends of said rectangular frames and the lower ends of said intermediate uprights 1. Upon the side of the uprights, opposite 5 the before-mentioned rectangular frames, are shorter uprights 9, to which is connected a horizontal beam 10, a similar beam being connected to the before-mentioned uprights 1 and to such additional shorter uprights 11 as may 10 be necessary for proper support, the said horizontal beams being connected by suitable cross-beams 12. At one end of the frame is a support 13 for the forming-machine D.

The hopper or reservoir.—The hopper or reservoir 15 illustrated is supported upon the horizontal bars 6 of the rectangular frames including such bars and is a tank or vat open at its top and provided with a discharge-opening 14 in its bottom. Suitable valve-plates 20 15 for controlling said opening slide upon the bottom wall of the hopper and between such bottom and suitable horizontal guides 16. Suitably journaled to the sides of the reservoir and extending across the same is a rock-shaft 17, from one end of which depends a rock-arm 18, which is connected by a link 19 with one of the before-mentioned valve-plates, and suitably pivoted upon the interior of one side wall of the reservoir is a bell- 25 30 crank lever 20, whose substantially vertical arm 21 is connected by a link 22 with the other of said valve-plates, the substantially horizontal arm 23 of said bell-crank lever being connected by a link 24 with an arm 25 35 upon the said rock-shaft. Oppositely-extending arms 26 upon the said rock-shaft are connected by a frame-link 27 with the vertically-movable rod 28 of a governor, said rod being moved and controlled by the governor- 40 45 arms 29 in a manner which will be readily understood. The governor is supported upon the upper cross-bar 2 of the frame, and its operating-shaft 30 is also supported upon said cross-bar and is provided with a suitable driving-pulley 31.

It will be noticed that each valve-plate covers a portion of the discharge-opening 14. By reason of the above-described connections between the rock-shaft 17 and the said valve- 50 plates said plates are given differential movement with relation to each other upon the rocking of said shaft, the plate connected to the link 19 moving through a greater distance for a given throw of the rock-shaft than does 55 the plate connected to the link 22, this difference of movement being clearly indicated by the dotted lines. The connection is such that upon the initial movement of the rock-shaft—*i. e.*, the movement imparted to said shaft by 60 the throw of the governing-arms due to the minimum speed of the operating mechanism—the valve-plate connected to the link 19 moves sufficiently to wholly clear the discharge-opening, so that the further regulations of the 65 discharge-opening due to increased speed is

effected wholly by the valve-plate connected to the link 22.

It is well known that with governors of usual construction the arms 29 are not moved through equal distances for corresponding 70 variations in speed of the mechanism by which the governor is driven, for the more nearly the governor-arms approach the horizontal the greater is the force required to throw them through a given arc. Therefore 75 if the rod 28 were connected to a governor of ordinary construction the valve-plates would not be moved through an equal distance for each equal variation in speed of the shaft which drives the governor, and for this reason 80 the supply of material from the vat would not be accurately proportioned to the speed of the operating mechanism. If, for example, the valve-plates would so move that the effective discharge-opening would be increased an 85 eighth of an inch for the first increase of ten revolutions above the minimum rotation of the shaft for the next increase of ten revolutions the effective opening of the discharge would be increased somewhat less than an 90 eighth of an inch, and so on. In the present apparatus the governor-arms 29 are levers of the first order, and the arms of these levers not provided with the weights are connected by the links 29^a to the vertical rod 28. This 95 connection results in causing the valve-plates 15 to be given an equal amount of movement for equal variations in speed of the shaft which drives the governor, notwithstanding the fact that the governor-arms 29 do not 100 move through equal arcs for equal variations in speed of said shaft.

The preliminary drying or bat-forming device.—Depending from the cross-bar 4 are hangers 32, in which is journaled a horizontal shaft 33, provided upon one end with a driving-pulley 34. Near one end of said shaft and intermediate the said hangers are radial arms 35, which are fixed to said shaft and form spokes supporting a rim 36, this rim and its spokes serving as a supporting-head for one end of a cylindrical screen 37, which lies intermediate the said hangers 32, the other end of said cylindrical screen being stiffened by a ring 38, secured to the same. Within said cylindrical screen is a cup or receptacle 39, which has its upper end open and can be conveniently a little more than half of a cylinder. The heads or ends 40 of said cup are provided with openings, through which the shaft 33 110 115 120 125 130 loosely passes, said heads being preferably provided about said shaft with antifriction-rollers 41. By reason of this construction the said cup hangs from the said shaft and remains substantially stationary at all times, while the screen rotates with the shaft. A suitable discharge-pipe 41^a leads from the lower portion of the said cup and extends outwardly through the space inclosed by the before-mentioned ring 38.

An inclined feed-trough 42, suitably supported from the before-mentioned bars 6, empties upon the periphery of the said screen 37, and upon the side of the vertical axis of 5 said screen opposite that upon which the conveyer-screen of the condensing mechanism is located a suitable flexible apron 43, preferably extending from the discharge end of said trough and resting upon the periphery 10 of the said cylindrical screen in a manner which will be readily apparent. A discharge 44 from the hopper or reservoir empties upon the said trough, so that material is delivered from the said reservoir A in a very fluid condition and reaches the revolving screen 37 in 15 such condition. After being delivered to the trough 42 it spreads upon said trough and is thus delivered over the whole width of the substantially broad rotating screen in a thin sheet. A great deal of the water readily falls 20 through the meshes of the said screen and is caught in the drip-cup 39, from which it is conveyed by the pipe 41, and the pulp is thus so dried that it is delivered from the said 25 screen in a thin bat.

I preferably provide means for preventing any possibility of the thin bat adhering to the bat-forming cylinder and being thus carried around by said cylinder instead of properly 30 deposited upon the carrier of the condensing mechanism. As here shown, this means comprises a pipe 85, which extends inside of the said screen and between the same and the drip-cup, said pipe having an elongated discharge-opening 86, so that air supplied to the 35 pipe is directed in a blast against the thin bat, near the lower portion of the screen. Thus as the screen rotates the thin bat is brought under the influence of the air-blast and is 40 blown from the supporting wire mesh.

The condensing mechanism.—Journalized between suitable standards supported upon the longitudinal horizontal frame-beams 10 are drums 45, which support an endless conveyer-screen 46, said conveyer-screen being below 45 the delivery-point of the rotating screen 37 and traveling in a line substantially at right angles to the plane of rotation of the said screen 37. Suitable brackets 47, near the 50 before-mentioned rollers 45 and intermediate the same, rise from the said beams 10 upon opposite sides of the said conveyer-screen and support cross-bars 48, upon which rest longitudinal beams 49, over which the upper portion 55 of the said conveyer-screen travels, so that said beams 49 support a portion of the weight of the pulp mass upon the said screen and prevent the latter from sagging. Cross-bars 50, supported upon the before-mentioned 60 brackets 47, extend above the said conveyer-screen and have longitudinal supporting-bars 51 connected thereto, said bars 51 being adjacent the edges of the said screen. Rising from said longitudinal bars 51 near the delivery 65 end of said conveyer-screen are a series

of bracket-plates 52, upon which are supported shafts 53 for condensing-rollers 54, said shafts 53 being preferably adjustably supported. The adjustability of these shafts can obviously be effected in many ways, and 70 in the present embodiment of my invention I have shown the bracket-plate as provided with vertical slots 55 in which the ends of the shafts are received, the shafts being clamped in adjusted positions in any convenient manner, as by providing one end of each shaft with a head 56 and the other end of said shaft with an adjusting-nut 57.

Resting upon the upper portion of the conveyer-screen is a frame having longitudinal 80 side bars 58, which preferably lie above the supporting-beams 49, and rising from the inner sides of said side bars are guide-plates 59, which are connected by suitable cross ties or braces 60, a cross-tie 61 also connecting the 85 said side bars 58 at what may be termed their "receiving" ends. A chain or other suitable flexible connector 62 has one end attached to said cross-tie 61 and its other end connected to some suitable relatively fixed member— 90 e. g., a plate 63 connected to and depending from the cross-bar 50 at the receiving end of the said screen. In this manner the guide-frame, which rests upon the screen, has certain freedom of movement and can thus adapt 95 itself to inequalities in the conveyer-screen, the said frame being thus permitted at all times to fit sufficiently closely upon the screen to prevent escape of pulp under the frame.

In order to control the end of the guide-frame near the delivery end of the conveyer-screen, I preferably provide the cross-bar 50 near said delivery end of the screen with a perforated lug 64 and provide a perforated lug 65 upon a suitable cross-bar or tie-bar of 100 the guide-frame, a guide-pin 66 extending through the perforations of the said lugs and being preferably fixed to the lug 64, the lug 65 having freedom of movement upon the said pin. The raceway or supply-trough 67, leading 105 to the forming-machine D, has its receiving end between the delivery ends of the said guide-plates.

From the foregoing description it will be apparent that the thin bat delivered from the 110 rotating drying or bat-forming screen 37 falls upon the conveyer-screen of the compressing mechanism, said bat being delivered between the guide-plates 59 of the before-mentioned 115 guide-frame. Owing to the fact that the said conveyer-screen 46 travels in a line at substantially right angles to the plane in which the bat-forming screen rotates, the whole width of the thin bat is delivered upon said conveyer-screen, thus permitting a relatively 120 large amount of pulp in such thin bat form to be fed to said conveyer-screen. Guided between the guide-plates 59 the pulp delivered to the 125 said conveyer-screen is carried beneath the compressing-rolls 54, and as these rolls are 130

preferably arranged at decreasing distances from the upper surface of the conveyer-screen the pulp is gradually condensed, and thus brought into the condition in which it is desired that it be fed to the forming-machine. From the condensing-rolls the screen feeds the pulp into the feed raceway or trough 67 of said machine.

In conjunction with the condensing mechanism I prefer to employ means for assisting in holding the pulp upon the conveyer-screen and for extracting some of the moisture in said pulp while the same rests upon said screen. Suitably supported intermediate the upper and lower parts of the conveyer-screen, as by connection with the supporting-beams 49, is a casing 68, whose open top is immediately below the pulp-carrying portion of said screen, an eduction-pipe 69 leading from said casing to the eye of a suitable exhaust-fan 70. I prefer to provide a trap 71 in the said pipe 69 intermediate the said casing and the said fan, said trap being conveniently provided with a draw-off cock 72. Thus the fan being operated air is exhausted from the said casing 68 and the pulp upon the conveyer-screen is consequently held upon said screen while certain of the moisture in said pulp is sucked into the casing 68. This moisture enters the pipe 69, but is prevented from being conveyed to the fan 70 by reason of the fact that before reaching such fan the moisture falls into the trap 71, from which it is discharged at desired intervals through the draw-off cock 72.

General organization and operation.—In the present embodiment of my invention 73 indicates the driving-shaft of the forming-machine D, this shaft being driven from any suitable source of power. Journaled upon the frame E is a longitudinally-extending horizontal main shaft 74, which is in driving connection with the shaft 73, as by means of beveled gears 75. One of the drums 45 is provided with a gear 76, which is connected in any convenient manner (as through the gear 77) with a gear 78, mounted upon a shaft 79, provided with a beveled gear 80, in mesh with a co-operating beveled gear 81 upon the main shaft 74. Pulleys 82 and 83 upon said main shaft are connected, respectively, with the before-mentioned pulleys 34 (upon the shaft of the bat-forming device B) and 31, (upon the governor-driving shaft 30.) Thus power for operating all of the moving parts of the present apparatus, including the forming-machine, is derived from a single source and the various moving parts are compelled to move at the desired speed with relation to each other. Furthermore, the supply of material from the hopper or reservoir A is proportioned to the amount of material delivered from the conveyer-screen 46 and operated upon by the forming-machine D.

In practice the gearing is such that the conveyer-screen 46 of the condensing mechanism

runs at a relatively low rate of speed, while the drying and bat-forming cylinder 37 runs at a somewhat higher rate of speed. Thus provision is made for supplying ample material to the conveyer-screen 46 in order to permit this material to be condensed into the desired condition for delivery to the forming-machine. The pulp in a highly-fluid condition is fed to the hopper or reservoir A in any suitable manner, passes in the desired quantity to the feed-trough 42, upon which it spreads into a thin sheet, and is delivered in this thin sheet to the drying and bat-forming device B. A great deal of the moisture passes from the pulp while upon the screen of this bat-forming device and is caught in the cup 39 and delivered from the apparatus, the pulp in a thin bat being delivered from the screen 37 to the conveyer-screen 46. While upon this conveyer-screen further moisture is extracted from the pulp and the pulp is conveyed to rolls, by which it is gradually condensed, the condensed pulp being then fed to the forming-machine.

I am aware that minor changes in the construction, arrangement, and combination of the several parts of my device can be made and substituted for those herein shown and described without in the least departing from the nature and principle of my invention.

Having thus described my invention, what I claim as new, and desire to secure by Letters Patent, is—

1. In an apparatus of the character indicated, means for spreading the pulp in a sheet, a pulp-receiving channel of less width than said sheet and into which channel said pulp is delivered from said spreading means, and pulp-condensing mechanism in said channel; substantially as described.

2. In an apparatus of the character indicated, a movable screen upon which the pulp is fed, a pulp-treating device, and a feed member between said movable screen and said pulp-treating device, said feed member and screen being at substantially right angles to each other; substantially as described.

3. In an apparatus of the character indicated, a member for forming the pulp into a web, a member for treating the pulp, and a feeding device between said web-forming and said pulp-treating members, said feeding device being substantially at right angles to said web-forming member; substantially as described.

4. In an apparatus of the character indicated, a traveling pulp-drying screen whose entire pulp-bearing surface is free from pressure, pulp-condensing mechanism, and means for feeding the dried pulp from said screen to said condensing mechanism; substantially as described.

5. In an apparatus of the character indicated, a reservoir having an opening, two valve-plates controlling said opening, each of said

- plates controlling a portion of said opening, and automatic governor mechanism in operative connection with each of said plates and including means for giving said plates differential movement with respect to each other; substantially as described. 5
6. In an apparatus of the character indicated, a reservoir having an opening, two valve-plates controlling said opening, each of said plates controlling a portion of said opening, a governor, and connection between said governor and said plates for giving said plates differential movement with respect to each other; substantially as described. 10
- 15 7. A reservoir having a discharge-opening, valve-plates controlling said opening, a rock-shaft, connection between said rock-shaft and said respective valve-plates, a governor, and connection between said governor and said rock-shaft; substantially as described. 20
8. The combination with a traveling conveyer adapted to receive the material being acted upon, of a guide-frame loosely supported upon said conveyer; substantially as described. 25
9. The combination with a conveyer adapted to receive the material being acted upon, of a guide-frame upon said conveyer having
- guide-plates forming a channel for the material, and a feed-pipe whose end lies between 30 said guide-plates; substantially as described.
10. The combination with a conveyer, of a guide-frame resting thereon, loose connection between one end of said frame and a relatively fixed support, and means for guiding 35 the other end of said frame; substantially as described.
11. The combination with a conveyer, of a guide-frame resting thereon, a relatively fixed support, a flexible connector between said support and one end of said frame, and a loose pin connection between said support and the other end of said frame; substantially as described. 40
12. The combination with supporting-beams, 45 of a conveyer traveling over the same, and deckles upon said conveyer and above and in line with said supporting-beams; substantially as described.

In testimony whereof I hereunto affix my 50 signature, in the presence of two witnesses, this 28th day of January, 1903.

JULIAN H. RIVERS.
